UNITED STATES PATENT OFFICE.

CARL SCHRAYSSHUEN, OF PROVIDENCE, RHODE ISLAND, ASSIGNOR TO SPEIDEL CHAIN CO., OF PROVIDENCE, RHODE ISLAND, A FIRM COMPOSED OF FREDERIC SPEIDEL AND EUGEN SPEIDEL, BOTH OF PFORZHEIM, GERMANY.

CHAIN OR BRACELET.

Application filed November 20, 1926. Serial No. 149,752.

This invention relates to an improved construction of chain; and has for its object to provide an ornamental chain band or bracelet having spaced chain strands extending the length thereof and having ornamental spacer members positioned between and connected to said chain strands at intervals along their length. A further object of the invention is that these chain strands are arranged alternately in close contact and widely spaced apart relation to form loops and to position an ornament in each loop opening to hold the loop strands separated.

A further object of the invention is to position a gem setting in the loop opening, the setting being attached to opposite edges of the strands to maintain the loop in fixed open position also to arrange the strands to cross alternately over and under each other between the loops whereby an ornamental chain of attractive appearance is produced.

With these and other objects in view, the invention consists of certain novel features of construction, as will be more fully described, and particularly pointed out in the appended claims.

In the accompanying drawings:

Figure 1 is a top view of the chain extended with the loops thereof maintained in open position by setting an ornament therein.

Figure 2 is an edge view of the chain showing the strands thereof as crossing alternately over and under each other with a gem setting in the openings between the points of crossing.

Figure 3 is an enlarged view of the gem setting and showing it as connected to the opposite edges of the strands to hold them in spaced relation.

Figure 4 shows a modified construction in which the strands of the chain are connected together between the loops without crossing each other.

In the construction of ornamental chains of this character, it is found that a very ornamental design is produced by providing two strands of flexible ornamental chain woven or braided together to pass alternately over and under each other at intervals along their length, the parts of the strands between the crossings being separated to provide a space in which an ornament such as a gem setting may be secured to perform the double function of first securing an orna-

mentation to the chain and second, to maintain the chain strands in fixed spaced relation between their points of crossing. The completed chain may be of any desired length to serve as a bracelet, neckchain, belt or girdle or for any purpose for which it is adapted, the chain being provided at its ends with suitable attaching means whereby the ends may be connected together or connected to some other article such for instance as a wrist watch, pendant or the like; and the following is a detailed description of the present embodiment of my invention and showing one means by which these advantageous results may be accomplished:—

With reference to the drawings, 10 designates the two strands of chain both of which are herein shown as being connected at one end to the bar 11 and at their opposite ends to the bar 12. These chain strands may be made up of any desired design of chain but preferably the chain should be flexible and ornamental in its character and these strands are herein shown as being arranged to cross alternately over and under each other at intervals along the length thereof as at 13, and that portion of the chain between the points of crossing are separated as at 14 to provide openings, spaces or loops 15. The opening in these loops being maintained of a fixed size or spaced by positioning another suitable ornamental member between the strands thereof, that herein shown being a gem setting 16, the opposite sides or edges of which are connected by solder or otherwise to the opposite inner edges 17 of the adjacent chain strands to hold these strands in fixed relation to each other intermediate the points of crossing. In this setting may be positioned any suitable design of gem 18 that herein shown being inserted from the bottom to rest against the upper inturned edge 19 of the setting and a ring-shaped setting member 20 is positioned from the bottom of the setting up against the under edge of the gem and this ring is held in position by the inturned bottom edge 21 of the band-shaped setting but in many instances the band is counterbored from its upper edge forming a shoulder against which the gem may rest.

In some instances instead of crossing the strands at intervals, I may simply bring them together side by side and connect them together either loosely or rigidly by a mem-

ber 25, if desired or any other arrangement of these side chain strands may be employed in which the chain strands extend the length of the bracelet or the like and support spacer members between them at intervals along their length.

My improved ornamental chain may be of any desired length to be employed as a band bracelet, as a wrist watch bracelet, as a necklace, girdle or for any purpose for which it may be adapted and connected to the cross bars 11 and 12 at the ends thereof.

I have herein shown eye members 21 on the bars to which are connected the attaching members 22 whereby the ends of this chain may be connected together or may be connected to any other article.

My improved ornamental chain is very handsome and attractive in appearance and by its general construction lends itself to a great variety of designs as stones or ornaments of any color, shape or size may be carried by the settings arranged in the openings along the length thereof.

25 The foregoing description is directed solely towards the construction illustrated, but I desire it to be understood that I reserve the privilege of resorting to all the mechanical changes to which the device is susceptible, 30 the invention being defined and limited only by the terms of the appended claims.

I claim:

1. A chain structure comprising two separate continuous flexible chain strands each 35 extending the length of the structure, secured together at their opposite ends and arranged to cross each other at intervals along their length, the strands being spaced apart between the points of crossing to form loops, 40 and an ornamental spreader member positioned between these strands in each opening to maintain the spread of the strands between these points of insertion.

2. A chain structure comprising two separate unbroken flexible chain strands extending the length of the structure, secured together at their opposite ends and arranged

to cross each other alternately over and under at intervals along their length, the strands being spaced apart between the 50 points of crossing forming loops in the chain, an ornamental spreading member positioned in the loop opening and secured to inside edges of the strands to maintain the loops in open arrangement.

3. A chain structure comprising two separate flexible chain strands extending the length of the structure, secured together at their opposite ends and arranged to cross alternately over and under each other at intervals along the length of the chain, the strands being spaced apart between the points of crossing to form open loops therein, said strands being unattached to each other at the points of crossing, and a gem 65 setting in said loop spaces attached to inside edges of said strands to maintain said loops in open position and gems mounted in the settings.

4. A chain structure comprising two separate flexible chain strands extending the length of the structure, a cross bar at each end of the strands securing them together, said strands being arranged to cross each other over and under alternately, the strands between the points of crossing being spaced a substantial distance apart forming open loops, an ornamental member in said loops secured to the strands thereof to maintain them in spaced relation, and attaching members connected to said end bars of the chain.

5. A chain structure comprising two separate flexible chain strands extending the length of the structure, secured together at their opposite ends and arranged in alternate widely-spaced and close contact formation the widely-spaced portions forming loops, and an ornamental spreader member in each loop to maintain the strands of the loop in spread position.

In testimony whereof I affix my signature.

CARL SCHRAYSSHUEN.
